UNITED STATES PATENT OFFICE.

EDWARD BECK, OF PITTSBURGH, PENNSYLVANIA, ASSIGNOR TO WESTINGHOUSE ELECTRIC & MANUFACTURING COMPANY, A CORPORATION OF PENNSYLVANIA.

MERCURY ARC RECTIFIER.

Application filed December 4, 1924. Serial No. 753,851.

My invention relates to mercury arc rectifiers and it has particular relation to mercury arc rectifiers that are started by tilting.

In the copending application of E. W. Breisch, Serial No. 404,251, filed August 17, 1920, and assigned to the Westinghouse Electric & Manufacturing Company, is described a mercury arc rectifier that is started by a tilting device employing a motor 10 parting to the rectifier a harmonic oscillatory motion. It has been found that tilting mechanisms of that character facilitate the starting operation since they combine a slow motion of the rectifier, at the moment when the 15 auxiliary starting electrode draws an arc upon the mercury surface, with a quick movement during the remainder of the operation.

My present invention constitutes an improvement upon the starting device described in the above-mentioned application and has, as one of its objects, the provision of a starting mechanism for producing a substantially harmonic oscillatory motion, 25 wherein all the parts that take part in the starting operation are mounted on a rigid unitary plate in a compact organization which is readily removable as a unit without endangering the adjustments of the 30 mechanism.

Another object of my invention is to provide a pivotally mounted rectifier and a concentrically pivoted oscillatory driving member, in combination with an electrically actuated coupling connecting the rectifier holder 35 and the driving member.

Another object of my invention is to provide an organization of the above-described character with means responsive to the initiation of the rectifier operation for entirely 40 de-energizing all the elements of the starting mechanism.

A further object of my invention is to provide a rectifier organization of the above-described character wherein, upon the initiation of the rectifier operation, the rectifier is automatically brought to its normal operating position, independently of the particular position of the tilting mechanism, and 45 wherein the circuits of the starting and tilting mechanisms are immediately de-energized.

A still further object of my invention is to provide a reliable tilting mechanism that is

inexpensive in first cost and economical in 55 operation.

The foregoing and other objects of my invention will be best understood by reference to the accompanying drawings, wherein—

Figure 1 is an elevational view of the back 60 side of the rectifier unit showing the rectifier and the assembled tilting mechanism,

Fig. 2 is a side view of the rectifier mechanism shown in Fig. 1,

Fig. 3 is an elevational view of the lower 65 portion of the motor driven tilting arm shown in Fig. 2, and

Fig. 4 is a diagrammatic view illustrating the electrical connections of a rectifier organized in accordance with my invention. 70

Referring to Figs. 1 and 2, the rectifier tilting mechanism is shown mounted upon a single plate 1 having bent-over edges 2 for increasing its rigidity. The supporting plate 1 extends across the full width of the panel 75 3 and is secured thereto by a plurality of bolts 4.

According to my invention, all the elements of the tilting mechanism of the rectifier are mounted upon the single supporting plate 1 and are so adjusted as to produce the optimum conditions of the starting motion. It is thus possible to dismount the starting mechanism as a single unit from the panel board 3 without disturbing the 80 operative relation of the several parts of the mechanism.

The tilting mechanism comprises a rectifier holder 6 secured to one end 7 of a shaft 8 that is supported by a bearing 9 which is 90 formed in a casting 10 that is secured to the supporting plate 1. The shaft 8 is disposed perpendicularly to the plate 1 and terminates at its other end in a knob 11 for tilting the rectifier by hand from the front 95 side of the panel.

The rectifier holder 6 carries, by means of clamps 12, a mercury arc rectifier of familiar shape such as that shown in Fig. 4. The rectifier comprises a glass vessel 15 having a mercury container 16 acting as a cathode, two arms 17 and 18 carrying the anodes 19 and 20, respectively, and a small container adjacent to the mercury cathode 16 holding mercury acting as an auxiliary 100 starting electrode 21.

Since the shaft 8 is freely rotatable in the bearing 9 and is above the center of gravity

of the rectifier bulb, the rectifier holder 6 will normally gravitate to a vertical position as shown in Fig. 1.

The casting 10 comprises a downwardly extending housing 22 on which is journaled a gear wheel 23 that is driven by a worm 24 mounted on the shaft 25 of an electric motor 26 that is secured to the supporting plate 1. The rotating gear wheel 23 is mechanically connected to a crank 28 which imparts an oscillatory motion to a swinging arm 29 that is loosely pivoted on the shaft 8 directly behind the rectifier holder 6.

The lower end 30 of rectifier holder 6 carries an electrically actuated latch mechanism 31 for providing a mechanical connection between the swinging arm 29 and the rectifier holder 6. The latch mechanism 31 is of simple construction comprising a magnetizable core member 32 constituting four sides of a rectangle with one side 33 hinged at a pivot 34 to provide a movable armature carrying a resilient supporting strap 35 terminating in a latch member 36 arranged to fit into a notch 37 in the lower edge of the swinging arm 29. The latch mechanism 31 is actuated by a latch energizing coil 38, carried upon the core 32. Upon de-energizing coil 38, the latch disengages the notch 37 under the action of the weight of the armature 33 and of an auxiliary helical spring 39.

Assuming that the motor 26 oscillates the swinging arm 29 through the worm 24 and gear wheel 23, and that the latch mechanism is de-energized, there will be no mechanical driving connection between the swinging arm 29 and the rectifier holder 6. If the coil 38 is energized, the hinged armature 33 will be pulled up, pressing the latch member 40 against the lower circularly shaped edge of the swinging arm 29 until the latch member snaps into the notch 37, thus perfecting a driving connection between the motor-operated swinging arm 29 and the rectifier holder 6. If the coil 38 is de-energized in any position during its oscillatory movement, the latch is released and the rectifier holder 6, together with the rectifier, gravitates back to its normal vertical operating position.

The provision of the latch mechanism and mounting the same upon the lower portion of the rectifier holder 6 adds directly to the weight of the rectifier holder increasing the force tending to bring the same downwardly to a vertical position. The spring member 35 is so mounted as to permit the latch member 36 to slide upon the curved surface of the swinging arm 29 and engage the notch 37 when the latch mechanism is energized.

The circuit connections of the rectifier described hereinbefore are shown in Fig. 4. An alternating-current supply line 41 may be connected through switches 42, and 43 switching members 43 to a pair of primary

coils 44 and 45 of a transformer 46. The coils 44 and 45 may be connected either in parallel or in series by placing the switching members 43 either as shown in the drawing by full lines or as shown in the drawing 70 by dotted lines.

The transformer 46 is provided with two main secondary windings 47 and 48 supplying a direct-current load 51 through the rectifier 15. The connection between the rectifier and the transformer coils 47 and 48 are effected by means of two dial switches 52 and 53 for adjusting the voltage supplied to the rectifier.

The dial switch 52 is arranged as a small 80 step dial and has a plurality of segments 54 and 55 leading to taps 56 and 57 on the transformer coils 47 and 48, respectively. Corresponding taps 56 and 57 may be connected through the contact holder 58 and 85 segments 59 to a common junction point 60, leading to the negative terminal of the direct-current load 51. The other dial switch 53 is arranged as the large-step dial and is provided with two sets of segments 61 and 62 leading to taps 63 and 64 disposed on the other ends of the transformer coils 47 and 48, respectively. The taps 63 and 64 may be connected by means of a contact holder 65 and terminal segments 66 and 67 and thence through reactors 68 and 69 to the anodes 19 and 20, respectively, of the rectifier 15. The cathode 16 of the rectifier is connected, through a sustaining reactor or choke coil 70 and an overload circuit breaker 71, to the positive terminal of the direct-current load 51.

The transformer 46 is also provided with a tertiary winding 72 for providing a source of energy to perform the starting operation. One terminal of the tertiary winding 72 is connected to the two terminals of a double-pole switch 73 and thence through one pole terminal 74 of the switch and a current-limiting resistor 75 to the starting electrode 110 21 of the rectifier. The other terminal of the tertiary winding 72 is connected to the rectifier cathode 16. The driving motor 26 of the tilting mechanism and the latch-energizing coil 38 are connected in parallel to the cathode 16 and the remaining terminal 76 of the double pole switch 73, through fuses 77.

The switch 73 which completes the circuits leading to the starting electrode 21, the driving motor 26 and the latch-energizing coil 38, is normally held in closed position by gravity and is automatically opened by means of a coil 78 which is connected in series with the lead extending between the junction point 60 of the secondary windings 47 and 48 and the direct-current load 51.

When the rectifier is started by energizing the transformer 46 through the line switch 42, the tertiary winding 72 energizes the tilt-

ing motor 26, the latch-energizing coil 38 and the rectifier starting circuit leading through the auxiliary starting electrode 21. The motor 26 thereupon oscillates the swinging arm 29, and the energized latch mechanism 31 effects a driving connection between the rectifier holder 6 and the oscillating arm 29, thus imparting to the rectifier an oscillatory motion during which the circuit within the rectifier, between the auxiliary electrode 21 and the cathode 16, will be opened, producing an arc upon the surface of the mercury cathode. After the first or second oscillation of the rectifier, an arch will ordinarily be struck between the main anodes 19 and 20 and the mercury pool and current will be supplied to the direct-current load 51. The series coil 78 of the switch 73 will thereupon be energized, opening the starting connections comprising the circuits leading to the auxiliary electrode 31, the motor 26 and the latch coil 38. The latch mechanism will instantly release the rectifier holder in whatever position it happens to be, and the rectifier will return to its vertical, normal position.

Should the operation stop for any reason whatsoever, for instance, by temporarily disconnecting the direct-current load, the series coil 78 will become de-energized, releasing the switch 72 and again completing the starting connections. Under such conditions, the rectifier will be tilted continuously, ready to start the rectifier operation at any time the direct-current load is connected again.

My invention was developed with a view to providing a simple, inexpensive and reliable rectifier set which will operate at the maximum efficiency and with a minimum of delays and disturbances. The principles disclosed in the specification are not necessarily limited to the particular details of construction shown and described herewith, and I desire that the appended claims shall be awarded the broadest construction consistent with the prior art.

I claim as my invention:

1. A tilting mechanism for a vapor rectifier, comprising a pivotally mounted rectifier holder, a member pivoted to swing around the pivotal axis of said holder, driving means for imparting a swinging motion to said member, and means for detachably coupling said member to said holder.

2. The combination with a vapor rectifier adapted to be started by tilting, of a tilting mechanism therefor comprising a pivotally mounted rectifier holder, a member pivoted to swing around the pivotal axis of said holder, driving means for imparting a swinging motion to said member, a coupling for connecting said holder to said member, and means responsive to the initiation of the rectifier operation for energizing and de-

energizing said driving means and said coupling.

3. The combination with a vapor rectifier adapted to be started by tilting, of a tilting mechanism therefor comprising a pivotally mounted rectifier holder, a member pivoted to swing around the pivotal axis of said holder, driving means for imparting a swinging motion to said member, a coupling for connecting said holder to said member, and a single relay responsive to the initiation of the rectifier operation for energizing and de-energizing said driving means and said coupling.

4. The combination with a rectifier having a cathode, a main anode and means adapted to start the rectifier by tilting, of a tilting mechanism therefor comprising a pivotally mounted rectifier holder, a member pivoted to swing around the pivotal axis of said holder, driving means for imparting a swinging motion to said member, an electrically operated coupling for connecting said holder to said member, and a single relay responsive to the current flowing through the main anode of said rectifier for de-energizing said driving means and said coupling.

5. The combination with a vapor rectifier adapted to be started by tilting, of a starting circuit therefor, means for energizing said starting circuit, a tilting mechanism for said rectifier comprising a pivotally mounted rectifier holder, a member pivoted to swing around the pivotal axis of said holder, driving means for imparting a swinging motion to said member, an electrically operated coupling for connecting said holder to said member, and means responsive to the initiation of the rectifier operation for simultaneously energizing or de-energizing said starting circuit, said driving means and said coupling.

6. A unitary tilting mechanism for a vapor rectifier comprising a bearing member, a shaft in said bearing member, a rectifier holder secured to said shaft, a swinging arm pivoted upon said shaft, a motor mechanism for imparting a swinging motion to said swinging arm, and an electrically actuated latch for coupling said holder to said swinging arm.

7. A unitary tilting mechanism for a vapor rectifier, comprising a bearing member, a shaft in said bearing member, a rectifier holder secured to said shaft, a swinging arm pivoted upon said shaft, a motor mechanism for imparting a swinging motion to said swinging arm, an electrically actuated latch for coupling said holder to said swinging arm, and a rigid supporting member for holding said bearing member and said motor mechanism in a definite relation as a detachable unit.

8. A unitary tilting mechanism for vapor

rectifiers, comprising a bearing member, a shaft in said bearing member, a rectifier holder secured to said shaft, a swinging arm pivoted upon said shaft, a motor mechanism for imparting a swinging motion to said swinging arm, an electrically actuated latch carried by said holder for coupling said holder to said swinging arm, and a rigid supporting member for holding said bearing member and said motor mechanism in a definite relation.

9. The combination with a pivotally mounted rectifier, of a driving member having a substantially harmonic motion, and an electrically actuated coupling mechanism connecting said rectifier and said driving member.

10. The combination with a pivotally mounted rectifier, of a driving member having a substantially harmonic motion, an electrically actuated coupling mechanism connecting said rectifier and said driving member, an electro-responsive means for simultaneously actuating said driving member and said coupling mechanism and for simultaneously rendering said member and mechanism inoperative, said rectifier being so mounted as to automatically return to a predetermined operating position regardless of the stopping position of said driving member.

11. In a rectifier starting mechanism, the combination with a supporting member, of a pivot secured at right angles thereto, a swinging rectifier holder and a swinging arm carried by said pivot for independent pivotal movement, a gear wheel mounted on a shaft parallel to said pivot, a continuously rotating motor geared to said gear wheel, a mechanical connection between said gear wheel and said swinging arm for causing the continuous rotation of the former to impart a swinging movement to the latter, and an electrically operated latch mechanism car-

ried by one of the swinging members for 45 detachably engaging the other.

12. In a rectifier starting mechanism, the combination with a supporting member, of a pivot secured at right angles thereto, a swinging rectifier holder and a swinging 50 arm carried by said pivot for independent pivotal movement, a gear wheel mounted on a shaft parallel to said pivot, a continuously 55 rotating motor geared to said gear wheel, a mechanical connection between said gear wheel and said swinging arm for causing the continuous rotation of the former to impart a swinging movement to the latter, an electrically operated latch mechanism carried by one of the swinging members for detachably 60 engaging the other, circuits for energizing said motor and latch mechanism in parallel with the rectifier, and a relay adapted, when energized, to open the circuits of both said motor and said latch mechanism, and, when 65 de-energized, to reclose said circuits.

13. In a rectifier starting mechanism, the combination with a supporting member, of a pivot secured at right angles thereto, a swinging rectifier holder and a swinging arm 70 carried by said pivot for independent pivotal movement, said rectifier holder being adapted to gravitate to a normal vertical position 75 in operation, a gear wheel mounted on a shaft parallel to said pivot and directly underneath the same, a continuously rotating motor geared to said gear wheel, a crank arm carried by said gear wheel and engaging vertical guides in said swinging arm for 80 imparting a swinging movement to the latter, and an electrically operated latch mechanism carried by one of the swinging members for detachably 85 engaging the other.

In testimony whereof, I have hereunto subscribed my name this 20th day of November, 1924.

EDWARD BECK.
